UNITED STATES PATENT OFFICE.

WILLIAM A. HAMMOND, OF OIL CITY, PENNSYLVANIA.

SAD-IRON.

SPECIFICATION forming part of Letters Patent No. 738,678, dated September 8, 1903.

Application filed October 23, 1902. Serial No. 128,409. (No model.)

To all whom it may concern:

Be it known that I, WILLIAM A. HAMMOND, a citizen of the United States, residing at Oil City, in the county of Venango and State of Pennsylvania, have invented certain new and useful Improvements in Sad-Irons, of which the following is a specification.

My invention relates to sad-irons, but more particularly to a detachable handle therefor, with means for attaching and detaching the handle to and from the iron proper.

The object of my present invention is to provide a sad-iron, a separable handle therefor of novel construction, means for quickly and easily connecting the handle to the iron and for disconnecting it therefrom.

Another object is to provide a sad-iron and handle therefor which will be strong and durable in construction, positive in action, in which the parts can be readily assembled and at the same time will be difficult of inadvertent displacement, which can be manufactured and sold at a comparatively low price and will be capable of a wide scope of usefulness and efficiency.

Another object is to reduce to a minimum the absorption of heat by the handle and the transmission of the heat to the hand of the operator and which will be easy of manipulation.

Other objects and advantages will appear from the following specification and from the drawings forming a part thereof.

With the above-enumerated objects in view my invention consists in a sad-iron embodying the improved construction, arrangement, and combination of the several parts hereinafter fully described, and pointed out in the claim.

In order to enable others skilled in the art to which my invention most nearly appertains to make and use the same, I will now proceed to describe and illustrate its construction and operation in connection with the accompanying drawings, in which—

Figure 1 shows a side elevation of my invention. Fig. 2 shows a central longitudinal section of the same. Fig. 3 is a detail of the operating-lever, and Fig. 4 is a detail top view of a portion of one end of the base of the handle.

Similar reference characters refer to similar parts throughout the several views.

In the drawings, A designates the metallic sad-iron, with the usual oval sides terminating in points *a* and *a'* at each end, the under surface being smooth and the upper surface being adapted to receive a handle in the manner hereinafter stated. The handle consists of the grip B, with uprights C and C' 55 extending down from each end thereof, the lower ends of the uprights being connected by a base member D, integral with the uprights. The base D extends out a slight distance at each end beyond the uprights, and 60 in each end of said projections are notches, as shown by 2 in Fig. 4. Rising above the center of the top of the iron A, near the right point *a'*, is a projection 3, which extends toward the center of the iron a slight distance, 65 forming a lip 4, the center portion of the space below the said lip being filled, forming a lug around which the notch 2 is adapted to fit. The tongues 5 and 5' extend under the lip 4 when the handle is attached to the iron. 70

The opposite end *a* of the iron A is provided with means for fastening which consist of the portion 8, rising above the surface of the iron, a lug 6, extending in from the center part of the portion 8, around which the notch 80 in the projection of the base D is adapted to fit. The lug 6 rises above the portion 8 and then extends outward, forming a lip 7, as shown.

Secured to the upper part of the upright C 85 by the screw 11 and extending down therefrom is a flat spring 9, the lower end of which is bent inward at right angles to its body portion, forming a lip 12, which is adapted to engage the lip 7 of the lug 6.

10 represents a reinforcing-spring which lies in contact with the spring 9 and is also secured by the screw 11 in the manner shown.

The operating-lever consists of a handle 13, with a T-head 14 at one end integral therewith and at right angles thereto, as shown in Fig. 3.

1 represents an opening in the upright C, through which the handle 13 may be inserted, the head 14 lying between the spring 9 and the upright C the lever will be held in place thereby.

It will now be seen, the construction being as shown and the handle being removed, that in order to attach the handle to the iron the grip B is taken in the hand of the operator, 5 the tongues 5 and 5' are inserted under the lip 4, the base is then brought down in contact with the surface of the iron by which the lug 6 is straddled by the tongues of the projection of the base D, the lip 12 of the spring 10 will be forced over the point of the lip 7 and engage between it and the portion 8, which will securely lock the handle in engagement with the iron, as shown in the drawings. In order to remove the handle, the operator 15 has only to lift up on the handle 13 with one finger of the hand which has hold of the grip B, which will cause the upper point of the head 14 to press the spring 9 outward, thus disengaging the lip 12 from the lip 7, when the handle can be lifted up disengaged from the iron A.

My invention is perfectly adapted to accomplish the results for which it is intended, and it is evident that changes in and modifications of the specific construction herein shown and described may be made and that analogous parts may be used to accomplish the same results without departing from the spirit of my invention or sacrificing any of 25 its many advantages.

Having now fully shown and described my

invention and the best mode for its construction and use to me known at this time, what I claim as new, and desire to secure by Letters Patent of the United States, is—

35

In a sad-iron, the combination with an iron A provided with a detachable handle, a base member D extending across between the lower ends of the uprights of the handle and adapted to contact with the upper surface of the iron A, 40 the base D extending out a slight distance at each end beyond said uprights with notches formed in each of said projections, said notches being adapted to receive the lugs which extend up from the top of the iron A, 45 a flat spring 9 secured at the top and extending down on the outside of one of said uprights of the handle with its lower point bent inward at right angles to engage the lip 7, a reinforcing-spring 10 lying substantially parallel to and in contact with the spring 9, and an operating T-head lever located in an opening through one of said uprights and held in place by said spring 9 contacting with said T-head, all substantially as described.

55

In testimony whereof I have hereunto signed my name to this specification in the presence of two subscribing witnesses.

WILLIAM A. HAMMOND.
